UNITED STATES PATENT OFFICE.

FREDERICK D. CLINTON, OF MILWAUKEE, WISCONSIN.

DESIGN FOR A SINK STRUCTURE.

60,318.

Specification for Design.

Patented Feb. 7, 1922.

Application filed September 9, 1921. Serial No. 499,567. Term of patent 14 years.

To all whom it may concern:

Be it known that I, FREDERICK D. CLINTON, a citizen of the United States, residing at Milwaukee, in the county of Milwaukee and State of Wisconsin, have invented a new, original, and ornamental Design for a Sink Structure, of which the following is a specification, reference being had to the accompanying drawing, forming part thereof.

In the drawing—

Figure 1 is a perspective view of a sink structure showing my new design.

Fig. 2 is a plan of the same.

I claim—

The ornamental design for a sink structure, substantially as shown.

FREDERICK D. CLINTON.
